CLOSURE

Adrian O. Daller, Dennisport, Mass., assignor to
 Daller Carton Co., Inc., New York, N. Y., a
 corporation of New York

Application July 12, 1933, Serial No. 680,022

10 Claims. (Cl. 229—51)

This invention relates to closures and more specifically to tight-seal closures.

In general, it is an object of the invention to provide a device of the character described, which 5 will efficiently perform the purpose for which it is intended, which is simple and economical of construction, which can be expeditiously and conveniently manipulated, and which is readily manufactured and assembled.

10 Another object of the invention is to provide a container, which may be opened to expose the entire face thereof, although there may be folding flaps along that face.

Another object is to provide a container having 15 folding flaps which will be torn aside by the raising of the cover.

Another object is to provide a container with a double cover, one part of which will be torn away from the adjacent part of the container and 20 which will ride upon the other part of the cover when the latter is raised.

Another object is to provide a container having a cover which is tight-sealed to certain folding flaps, but which may be easily broken away 25 therefrom when the cover is raised.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and 35 objects of the invention reference should be had to the following detailed description taken in connection with the accompanying drawings, in which:

Fig. 1 is a view in perspective of a device embodying one form of the invention, the cover being shown before sealing;

Fig. 2 is a perspective view of the device shown in Fig. 1, certain parts of the cover having been sealed;

Fig. 3 is a perspective view of the device shown in Fig. 1, the sealed cover being shown as broken open;

Fig. 4 is a perspective view of the device shown in Fig. 1 sealed and enclosed in a wrapper; and

50 Figs. 5, 6 and 7 are perspective views respectively similar to Figs. 1, 2 and 3 of a modification of the device shown in Fig. 1.

This invention is concerned with means for closing and opening. It will be described in connection with the cover of a container. The opening can, of course, also be used at an end, side or bottom of the container.

In the drawings, the numeral 10 denotes a container made of any suitable material and in any 55 suitable fashion either from one or more pieces

of material. The sections or folding tabs 11 are folded to extend at least in part over the top of the container and may be integral with or connect with some other portion of the container, such as the ends 12. A score line 13 separates the tab 11 from the end 12 and is usually placed along the edge of the container. It may, however, be on either side of said edge. A cover section 14 is adapted to be folded down over the tab sections 11 and be secured to them by any proper means as, for example, by an adhesive. The cover section is hingedly connected to an adjacent section, which may be the back 15 of the container. This hinge 14' may be simply a bend in the material. Another section 16 is 15 adapted to be folded down over section 14 and to be secured thereto. It may be attached to a front section 17 of the container which may be opposite the back section 15, and at an angle with the ends 12. A score line 18 is provided separating the section 16 from the integrally-adjacent portion of the container. The score line may be along or on either side of the top front edge, for example. Preferably, a deviation in this score line takes in a part of the adjacent portion of the 25 device, so as to form a tab 19.

In assembling the device, the tab sections 11 are folded in, the section 14 is secured to the sections 11 and section 16 is folded down upon and secured to section 14. When it is desired to 30 open the device, the score line 18 is broken and tab 19 is taken hold of and raised, with the result that the cover 16 is pulled up with the cover 14 underlying it and the sections 11 are broken along their score lines 13, so that they also ride 35 on the under side of the cover. In this way the tight-sealed package is completely opened to give a wide-open face, through which all of the contents of the box may be immediately dispensed.

40 The carton sealed and enclosed in a wrapper 21 is shown in Fig. 4. The wrapper may be sealed to the carton on one or more of the sides, top or bottom. It may have a score line 18' in registry with the score 18 and/or there may be indicia 45 showing where the wrapper is to be broken. The score line 18' may extend along the sides of the top of the carton.

In Figs. 5, 6 and 7 there is shown a modification of the above-described device. Score lines 50 20 on the cover section 14 define areas which, when the cover section is closed, are superimposed over the tabs 11. The cover section is secured to the tabs in the areas which are at least partly defined by the score lines 20. There need be no 55 score lines on the tab sections 11. Otherwise the construction is the same as hereinabove described. In opening the box, the score line 18 is broken, the tab 19 is used to raise the cover section 16, which pulls with it the cover 14 so that both 60

pivot about the hinge 14' of the latter. The areas defined by the score lines 20 remain secured to the tabs 11, and the score lines 20 break away.

Since certain changes may be made in the above article and different embodiments of the invention could be made without departing from the scope thereof, it is intended that all matter contained in the above description or shown in the accompanying drawings shall be interpreted 10 as illustrative and not in a limiting sense.

It is also understood that the following claims are intended to cover all of the generic and specific features of the invention herein described, and all statements of the scope of the invention which as a matter of language, might be said to fall therebetween.

Having described my invention, what I claim as new and desire to secure by Letters Patent, is:

1. In a device of the character described, the combination comprising a section, a score line separating said section from the integrally-adjacent portion of said device, a second section secured to and overlying said first section and hinged to an adjacent portion of said device, a third section secured to said second section, and a severable score line entirely separating said third section from the integrally-adjacent portion of said device, said three sections being hingedly movable as a unit after the severing of 10 said score lines and said second section being integral with the same portions of said device after said severing as before.

2. In a device of the character described, the combination comprising a section, a score line separating said section from the integrally-adjacent portion of said device, a second section secured to and overlying said first section, a third section secured to said second section, and a severable score line entirely separating said third section from the integrally-adjacent portion of said device, said second and third sections extending from opposite walls of said device, said three sections being hingedly movable as a unit after the severing of said score lines and said second section being integral with the same portions of said device after said severing as before.

3. In a device of the character described, the combination comprising a section, a score line separating said section from the integrally-adjacent portion of said device, a second section secured to and overlying said first section, a third section secured to said second section and a severable score line entirely separating said third section from the integrally-adjacent portion of said device, said second section overlying said first section and said third section overlying said second section, said three sections being hingedly movable as a unit after the severing of said score lines and said second section being integral with the same portions of said device after said severing as before.

4. In a device of the character described, the combination comprising a folding tab, a score line separating said tab from the wall to which it is attached, a hinged cover overlying and adhesively secured to said tab, a second cover overlying and adhesively secured to said cover, and a severable score line entirely separating said second cover from that part of the device to which it is attached and including at least some of said part, said tab, hinged cover, and second cover being hingedly movable as a unit after the severing of said score lines, and said hinged

cover being integral with the same portions of said device after said severing as before.

5. In a device of the character described, the combination comprising a section, a score line separating said section from the integrally-adjacent portion of said device, a second section secured to and overlying said first section, a third section secured to said second section and a score line separating said third section from the integrally-adjacent portion of said device, 10 said second section remaining intact after said score lines are severed and said intersecured sections being hingedly movable, after the severance of said score lines, said intersecured portions being in one wall of said device and hingedly associated with another wall of said device along a portion of said second section, which portion is integral with said other wall.

6. In a container, in combination, a layer comprising folding tabs extending from opposite walls, 20 a second layer comprising a hinged cover adhesively secured to said tabs, one of said layers overlying the other of said layers, score lines in one of said layers setting off areas in registry with certain areas in the other of said layers, a 25 third layer comprising a cover overlying and adhesively secured to said second layer, a score line separating at least a portion of said last-mentioned cover from that part of the device to which it is attached, and a side wall, said intersecured 30 layers being hingedly attached to said container, after said score lines are severed, along that edge of said second layer which is common to said intersecured layers and said side wall.

7. In a container, in combination, a layer comprising folding tabs extending from opposite walls, 35 a second layer comprising a hinged cover adhesively secured to said tabs, one of said layers overlying the others of said layers, score lines in said first-mentioned layer setting off areas in registry with certain areas in the other of said layers, a third layer comprising a cover overlying and adhesively secured to said second layer, a score line separating at least a portion of said last-mentioned cover from that part of the device to 40 which it is attached, and a side wall, said intersecured layers being hingedly attached to said container, after said score lines are severed, along that edge of said second layer which is common to 45 said intersecured layers and said side wall.

8. In a device of the character described, a wall comprising a section, a severable score line entirely separating said section from the integrally-adjacent portion of said device, a second section secured to said first section and having no 55 score line associated therewith, a third section secured to said second section and a severable score line entirely separating said third section from the integrally-adjacent portion of said device.

9. In a device of the character described, the combination comprising a first section, means to facilitate the severance of said section from the integrally adjacent portion of said device, a second section secured to and overlying said first section and hinged to an adjacent portion of said device, a third section secured to said second section and integral with but severable from an adjacent portion of said device, said three sections being hingedly movable as a unit after said first and 65 third sections have been severed from their respective said integrally adjacent portions, and the said second section remaining integral with that portion of said device to which it is hinged after said severing.

10. A carton comprising front, back, side, bottom and top walls, one of said walls comprising in overlying and secured relation a tuck flap and two cover sections, means to facilitate the severance of the tuck flap from that adjacent wall of the container with which it is normally integral, and means to facilitate the severance of one of said cover sections from that adjacent wall

of the container with which it is normally integral, whereby when said tuck flap and said severable cover section have been severed from their respective said adjacent walls said tuck flap and said two cover sections form a hingedly movable extension of an adjacent wall of said container.

5

ADRIAN O. DALLER.
